GUARDED VENT FITTING

Hugh Long, Los Angeles, Calif.

Application November 20, 1939, Serial No. 305,276

8 Claims. (Cl. 285—210)

This invention relates to a fitting utilized in connection with plumbing installations.

Drains are commonly installed for connection, through a trap if desired, to a pipe or conduit that disposes of the waste, either through a sewer or other disposal means. It is required that an upwardly directed vent pipe be installed, above the pipe or conduit. To effect this, use is made of a vent fitting, that joins the drain pipe to the downwardly directed soil pipe, and also provides a support for the vent pipe.

Such vent fittings as commonly installed, permit rapid clogging of the opening to the vent pipe with greasy material carried past the opening by the waste water. This clogging would interfere very materially with the venting function. It is one of the objects of this invention to retard the accumulation of such material in the passages leading to the vent pipe.

It may be necessary at times to insert a flexible "snake" through the drain and into the soil pipe, for opening a clogged pipe. When the snake passes through the vent fitting, it is apt to be deflected thereby and proceeds upwardly through the vent pipe, instead of downwardly through the soil pipe, as intended. It is still another object of this invention to obviate such occurrences.

It is a further object of this invention to facilitate the flow of waste matter into the soil pipe from the drain, and to retard the entry of such matter upwardly into the vent pipe.

These objects are accomplished by the provision of a fitting of definite configuration. Although such a fitting may be of especial utility in connection with vent pipes for use in the disposal of waste, yet the fitting may be utilized to promote smoothness of flow of fluids around bends and through the fittings; as for example in steam or water pipes.

This invention possesses many other advantages, and has other objects which may be made more easily apparent from a consideration of several embodiments of the invention. For this purpose there are shown a few forms in the drawing accompanying and forming part of the present specification. These forms will now be described in detail, illustrating the general principles of the invention; but it is to be understood that this detailed description is not to be taken in a limiting sense, since the scope of the invention is best defined by the appended claims.

Referring to the drawing:

Figure 1 is a sectional view of an embodiment of the invention;

Fig. 2 is a sectional view taken along plane 2—2 of Fig. 1;

Fig. 3 is a sectional view taken along plane 3—3 of Fig. 1; and

Fig. 4 is a view similar to Fig. 1, of a modified form of the invention.

In the embodiment illustrated in Figs. 1, 2 and 3, the vent fitting body 1 is shown as having a plurality of openings into which the various pipe or conduit elements may be joined. These openings in the present instance may be conveniently formed by the threaded extensions 2, 3 and 4. The threaded extensions 2 and 4 may be in virtual alignment at opposite ends of the hollow vent fitting body 1. Of course, provisions other than threads, for attaching the conduits in fluid tight manner in the openings may be provided. The extension 3 is arranged so as to be intermediate and transverse to the extensions 2 and 4. Into it may be attached the conduit 5, that may lead from a drain or trap.

The waste matter passing through conduit or pipe 5 is intended to pass into the body 1, and downwardly through the downwardly directed soil pipe or conduit 6, which may connect to an appropriate drainage sewer. The upwardly directed passage or conduit 7 is intended in this instance to act as a vent pipe, necessary in plumbing installations of this character, to carry off waste gases.

It has been found that in ordinary vent fittings of this character, greasy waste matter may collect in the bottom of the vent pipe 7, thereby reducing its effectiveness and interfering with its function. Furthermore, in the event that it may be necessary to insert a snake through conduit 5 and into conduit 6 for clearing the waste passages, the snake may be deflected upwardly into the vent pipe 7 instead of downwardly into the soil pipe 6. By appropriate configuration of the vent fitting body 1, the danger of clogging of the vent pipe 7 is obviated, and there is greater assurance that any cleaning medium, such as a snake, will be properly directed downwardly into the conduit 6.

For this purpose the wall 37 opposite the opening formed in extension 3 is shown as having a concave inner surface 8. The waste from conduit 5 impinges against this concave surface 8 and is directed by this concavity downwardly in the general direction illustrated by the arrows 9 and 10.

The upward flow of the waste is prevented by a deflector formed at the upper end of the surface 8, as by the aid of a ridge or projection 11.

(Figs. 1 and 3). This ridge or projection 11 is joined to the concave surface 8 by an intervening deflecting surface 12, which may be concave or flat as desired. As shown most clearly in Fig. 3, this deflector ridge 11 extends arcuately around the body 1 for about 180 degrees, decreasing in depth as the ends of the ridge are approached. The deflecting surface 12 is located immediately below the conduit 7. The edge of ridge 11 is formed in a point by the meeting of the deflecting surface 12 and the sloping surface 13, leading upwardly toward the bottom of conduit 7. This sloping surface 13, together with the opposite sloping surface 14 on the body 1, defines a substantially round upwardly sloping passage 15, leading from the inner end of conduit 5 to the lower end of conduit 7.

Due to this slanting passageway 15 and the ridge 11, waste matter entering the body 1 through conduit 5 will find its most ready passage to be in a downward direction through the pipe 6. The waste impinging upon the surface 8 will not spatter upwardly but will be deflected downwardly in the proper direction as indicated by arrows 9 and 10.

In the form of the invention illustrated in Fig. 4, the vent fitting body 16 is shown as adapted to accommodate a pair of oppositely directed drain pipes or conduits 17 and 18, to form a common fitting for both conduits. These drain pipes or conduits 17 and 18 are arranged transversely to the direction of the vent pipe 19 and the soil pipe 20. In this instance, an intermediate wall 21 is illustrated, forming the deflecting surfaces 22 and 23 respectively opposite the conduits 17 and 18. These surfaces 22 and 23 slope so as to deflect waste matter entering these conduits 17 and 18 downwardly into the pipe 20. Immediately above the transverse wall 21, and formed as continuations of surfaces 22 and 23 are the deflecting surfaces 24 and 25. These deflecting surfaces operate in a manner similar to the deflecting surface 12 in the form illustrated in Fig. 1. They are formed below the circular ridges 26 and 27; each of these ridges has an upward slant, meeting at an acute apex 28 centrally of the axis of the vent pipe 19. These sloping surfaces 26 and 27 also form with the walls of body 16, upwardly directed slanting passageways 29 and 30, respectively between conduit 17 and vent 19, and between conduit 18 and vent 19.

The manner of operation of this form of the fitting is substantially the same as that described in connection with the fitting illustrated in Fig. 1. The waste entering through the conduits 17, 18 may impinge upon the surfaces 22 and 23. This waste is thereby deflected to travel along the direction of the arrows 31, 32. At the same time the surfaces 24 and 25 protect the vent pipe 19 from accumulation of foreign matter.

What is claimed is:

1. In a hollow fitting having openings for connection to a pair of oppositely directed conduits as well as to another conduit that is intended to be angularly displaced from said pair, a wall forming a surface in said fitting opposite the opening for said other conduit, said surface having a sloping configuration extending substantially across the opening of said other conduit, to guide substantially all of the liquid entering from said other conduit into one of the pair of oppositely directed conduits and away from the other of the pair, and a ridge extending partly around the said surface and opposite the edge of

said opening, and overhanging said surface, to prevent separation of the stream of liquid between said pair.

2. In a hollow fitting having oppositely directed openings as well as another opening intermediate said oppositely directed openings, a wall having a surface opposite said intermediate opening, said surface having a continuous slope that extends substantially across the said intermediate opening, to deflect substantially all of the liquid entering through the said intermediate opening, into one of said oppositely directed openings, and away from the other of said oppositely directed openings, and a deflector joining 10 the top of the continuously sloping surface and below said other of the oppositely directed openings, the deflector and said surface thus forming a ridge at the top of said surface.

3. In a hollow fitting having oppositely directed openings as well as another opening intermediate said oppositely directed openings, a wall for the fitting having an interior surface opposite said intermediate opening, said interior surface being concave for directing flow of fluid

25 to one of said oppositely directed openings, and a ridge on said surface and below the other of said oppositely directed openings, said ridge forming a deflecting surface partly around the axis of said other oppositely directed opening and forming a 30 continuation of said concave surface, said ridge also forming a sloping surface extending toward the said other oppositely directed opening, the said sloping surface forming the deflecting surface in an acute angle.

4. In a hollow fitting having oppositely directed openings as well as another opening intermediate said oppositely directed openings, a wall for the fitting having a surface opposed to said intermediate opening, said surface extending 40 substantially across the said intermediate opening, for guiding substantially all of the liquid from said intermediate opening to one of said oppositely directed openings, and a ridge on said surface and below the other of said oppositely directed openings, said ridge forming a deflecting surface as a continuation of said wall surface, said ridge also forming a sloping surface extending toward the said other oppositely directed opening, the said sloping surface joining 45 the deflecting surface in an acute angle.

5. In a hollow fitting having oppositely directed openings as well as another opening intermediate said oppositely directed openings, a wall for the fitting having a surface opposed to

55 said intermediate opening for guiding fluid from said intermediate opening to one of said oppositely directed openings, a ridge on said surface and below the other of said oppositely directed openings, said ridge forming a deflecting surface

60 as a continuation of said wall surface, said ridge also forming a sloping surface extending toward the said other oppositely directed opening, the said sloping surface of the ridge joining the deflecting surface in an acute angle, and a wall 65 having an interior surface forming with said sloping surface of the ridge, a sloping round conduit between the intermediate opening and said other oppositely directed opening, said deflecting surface decreasing in width around the interior of said sloping conduit.

6. In a hollow fitting having a pair of oppositely directed openings as well as another pair of oppositely directed openings along a line transverse to the first pair, a wall within said fitting and interposed between said other pair

of openings, said wall having opposite sides for guiding fluid respectively from both of said other pair of openings to one of the first pair of oppositely directed openings, and a projection on said wall for deflecting fluid from the other of said first pair of oppositely directed openings. 5

7. In a hollow fitting having a pair of oppositely directed openings as well as another pair of oppositely directed openings along a line transverse to the first pair, a wall within said fitting and interposed between said other pair of openings, said wall having opposite sides for guiding fluid respectively from both of said other pair of openings to one of the first pair of oppositely directed openings, and a ridge on said wall and below the other of said first pair of oppositely directed openings, said ridge forming deflecting surfaces as continuations of the opposite wall surfaces, as well as a pair of oppositely sloping surfaces extending toward the said other of the first pair of oppositely directed openings, the said sloping surfaces meeting in an apex below said other of the first pair of oppositely directed openings, and joining the deflecting surfaces in an acute angle. 10 15 20

8. In a hollow fitting having a pair of oppositely directed openings as well as another pair of oppositely directed openings along a line transverse to the first pair, a wall within said fitting and interposed between said other pair of openings, said wall having opposite sides for guiding fluid respectively from both of said other pair of openings to one of the first pair of oppositely directed openings, and a ridge on said wall and below the other of said first pair of oppositely directed openings, said ridge forming deflecting surfaces as continuations of the opposite wall surfaces, as well as a pair of oppositely sloping surfaces extending toward the said other of the first pair of oppositely directed openings, the said sloping surfaces meeting in an apex below said other of the first pair of oppositely directed openings, and joining the deflecting surfaces in an acute angle, said fitting having walls with interior surfaces forming with said sloping surfaces, sloping round conduits respectively between the said other pair of oppositely directed openings, and said other of the first pair of openings. 25
